UNITED STATES PATENT OFFICE

143,875

DESIGN FOR A DUPLICATOR

Joseph Palma, Chicago, Ill., assignor to Niagara
Duplicator Co., a corporation of California

Application June 12, 1945, Serial No. 120,039

Term of patent 14 years

(Cl. D64—11)

To all whom it may concern:

Be it known that I, Joseph Palma, a citizen of the United States residing in the city of Chicago, county of Cook, and State of Illinois, have invented a new, original, and ornamental Design for a Duplicator, of which the following is a specification, reference being had to the accompanying drawing, forming a part thereof.

In the accompanying drawing the figure is a

perspective view of a duplicator, embodying my new design. The rear of the duplicator not shown is substantially the same as the front except that the handle is omitted, and the opposite end is similar to the end shown.

I claim:

The ornamental design for a duplicator, substantially as shown and described.

JOSEPH PALMA.
